UNITED STATES PATENT OFFICE.

JOEL B. LOW, OF SAN FRANCISCO, CALIFORNIA.

ROPE RAILWAY.

SPECIFICATION forming part of Letters Patent No. 288,646, dated November 20, 1883.

Application filed December 17, 1881. (No model.)

To all whom it may concern:

Be it known that I, JOEL B. LOW, of the city and county of San Francisco, State of California, have invented an Improvement in 5 Rope Railways, of which the following is a specification.

My invention relates to the manner of operating the grip which connects the car with the underground moving rope; and it consists in placing the grip upon a frame carried by and between the axles of the main passenger-car, and operating said grip by any suitable machinery from either end of the said car, or by such a device as is herein described. 15 The object is to avoid the use of a separate car or "dummy" to carry the grip, and at the same time to avoid obstructing the interior of the car by grip-operating machinery.

In the accompanying drawings, Figure 1 is 20 a plan of my invention, taken below the line of the floor of the car, the center part of which floor is shown broken away, the better to view the parts below. Fig. 2 is a side view of the invention, the near wheels of the car being removed. Figs. 3 and 4 are enlarged views of 25 details, as indicated by reference-letters.

In all the figures of the drawings like letters represent like parts.

A is the floor of an ordinary street-car; B, 30 the front and B' the rear platform.

C C C C are the wheels of the car, and D D the axles.

E is a stout iron hanger, which is supported by the axles D D. This hanger is composed 35 of the two bars e e and the two sleeves e' e', to which the bars are fastened. The sleeves fit upon the axles D D, and are held from lateral movement by reason of the axles being turned down to a smaller diameter where the sleeves 40 occupy their length, so as to form a shoulder at each end of each sleeve. Collars and set-screws, however, may be used at each end of the sleeves for the same purpose. The sleeves are made in halves and bolted together, as 45 shown in Figs. 1 and 2. The bars e e are depressed in the middle, as shown in Fig. 2, to give room for the working parts, which set upon them and below the floor of the car.

Upon the bars of the hanger I provide four 50 straps or stirrups, F, which are firmly bolted

to these bars, and form guides and bearings in and through which the cross-bars G G pass, so that these cross-bars may be firmly held down while being permitted, each independently, to move endwise. It is upon these 55 cross-bars that the grip is secured, their use being to provide a necessary adjustability for the grip, both as to its height in relation to the rope H and its position relative to the slot in the road-bed. The cross-bars have the 60 standards g g, standing vertically in about the middle of each bar. They receive the grip I by being inserted through the holes in the hubs formed on each end of the tie-frame i of the grip. As the grip herein illustrated is the 65 one patented to Grim and Low, August 16, 1881, No. 245,627, it will be unnecessary to enter further into the details of its construction. Reference may be made to said patent for a description in detail. It has of course been 70 necessary to make some changes in the grip to adapt it to the conditions of my new way of operating it. Some of the parts have been left out and others have been added.

There is placed upon the shaft or axle of the 75 cam or eccentric a spur-gear wheel, J. This wheel is moved to the right or left in operating the grip by a rack-gear, K, which slides back and forth in a suitable guide or bearing, L, bolted to the stationary side bars of the 80 grip. The rack-gear K is connected from each end to two other rack-gears, M M, supported in suitable guides or bearings, N N, which are fastened under the extreme end of the platforms B B'. The connections are made by the 85 rods O O. In making the joint between the rods O O and the rack-gears the fact must be observed that one rack is attached to the car-body, which, being supported on springs, varies its height according to the load it carries, 90 the variation often exceeding two or three inches, while the other rack is attached to the grip, adjustable both as to its height and horizontal position. For this reason it would be best to allow some flexibility in these joints, 95 though the spring of the rods, where they are long enough, may often answer all purposes. It may be preferred in some cases to support these rods in guides fastened on the car bottom. In such cases an intermediate flexible 100

link in the rod may be provided at the grip end. This matter may be left, however, to the discretion of the constructer. The rack-gears M M engage with the spur-pinions P P, which are loosely fitted to the lower ends of upright rods Q Q.

R R are hand-wheels secured to upper ends of rods Q Q, by which the rods are turned.

S S are ordinary ratchet-wheels, which, together with the pawls T T, serve to check the rods Q Q backward when the operator releases his hold of the hand-wheels.

U U are disks loosely fitted on shafts Q Q, either cast solid with or in some way fastened to the pinions P P. They are perforated with six or eight holes at such a distance from the center as will correspond with a hole which is perforated in each of the ratchet-wheels S S.

V is a pin, which, when passed through the hole in one of the ratchet-wheels and into one of the holes in the disk U, immediately below it, serves to lock the two together, so that when the upright shaft is turned by the hand-wheel, the pinion, though loose on the shaft, is revolved with it. When this pin is removed, the pinion cannot be turned by turning the hand-wheel. There being but one pin, the engineer carries it with him from one end of the car to the other, thus insuring that no one can operate the other end in his absence—a matter of necessary precaution to avoid accidents. The upright shafts are supported on the frames W W, which project from underneath the car-platform, a suitable metal step being provided to receive the point of each shaft. Bearings for these shafts are also attached to the rails of the platform, exactly like the ordinary brake-wheel shafts.

The brake for the car is precisely as ordinarily used. I do not wish to confuse my drawings by showing it, and as it forms no part of my invention I need not describe it here.

Immediately over the grip there is provided in the floor of the car a trap-door sufficiently large to pass the grip through. Generally the grip is put in place whenever the car goes into service and removed when it returns from service. Sometimes it is required to be taken up or examined in the middle of a trip.

In the class of railways to which this invention relates the engineer must always have an unobstructed view of the track in front of him. This necessitates his occupying the front platform, which is at one end of the car or the other, as the car is going out or returning on its trip, in cases where the car is not turned around at the termini. He therefore requires

a set of machinery at each end in such cases; but if the arrangement of the road permits the car to be turned end for end at the termini, then but one set of operating rods and gears need be supplied.

The operation of the device may be summed up as follows: The car being ready to start, the engineer inserts the pin through the ratchet-wheel and disk. He then turns the hand-wheel so as to cause the pinion to act on the rack M, so as to draw the rod O toward it, motion being thus transmitted to the gear on the cam-shaft of the grip, to the effect of raising the bar, which in this grip operates to close the jaws tightly on the rope, a reverse motion releasing the rope from the jaws. (See patent before mentioned.)

In very many cases the engineer can act as conductor also, and thus economize expenses.

What I claim as my invention, and desire to secure by Letters Patent, is as follows:

1. In a rope railway with underground rope, the combination, with an ordinary passenger-car, of a rope-gripping device extending through a narrow slot in an underground tube and therein gripping the rope, said gripping device being set underneath the floor of the car in a position central to the group of supporting-wheels, and suitable mechanism at one or both ends of the car for operating said gripping device.

2. In a rope railway with underground rope, the combination, with an ordinary passenger-car, of a rope-gripping device supported by and between the wheel-axles, and suitable mechanism at one or both ends of the car for operating said gripping device.

3. In a rope railway with underground rope, the combination, with the passenger-car, of the hanger E, grip I, with gear J, rack K, rod O, rack M, pinion P, and shaft Q, arranged and operated as and for the purpose herein described.

4. In a rope railway with underground rope, the combination, with an ordinary passenger-car, of a rope-gripping device extending through a narrow slot in an underground tube and gripping the rope therein, said gripping device being set entirely underneath the car-floor, and suitable mechanism leading from said gripping device to the end of the car beyond the entrance-platform, substantially as and for the purpose described.

JOEL B. LOW.
